(57) **CLAIM**

The ornamental design for a needle dispensing and storage device with removable columns, as shown and described.

DESCRIPTION

FIG. 1 is a front isometric view of a needle dispensing and storage device with removable columns.

FIG. 2 is a front side elevation view thereof.

FIG. 3 is a back side elevation view thereof.

FIG. 4 is a right side elevation view thereof.

FIG. 5 is a left side elevation view thereof.

FIG. 6 is a top plan view thereof.

FIG. 7 is a bottom plan view thereof.

FIG. 8 is a front isometric view of a needle dispensing and storage device with removable columns with one of the columns removed, it being understood that all other surfaces are the same as the other views of this storage column component and that all of the columns are removable.

FIG. 9 is a front isometric view of a column of the storage device removed from the storage device, it being understood that all other surfaces are the same as the other views of this storage column component.

FIG. 10 is a front side elevation view thereof.

FIG. 11 is a back side elevation view thereof.

FIG. 12 is a right side elevation view thereof.

FIG. 13 is a left side elevation view thereof.

FIG. 14 is a top plan view thereof; and,

FIG. 15 is a bottom plan view thereof.

The features shown in broken lines in the drawing depict environmental subject matter only and form no part of the claimed design.
